UNITED STATES PATENT OFFICE.

WILHELM WINTER AND GERHARD IMMAND, OF ESSEN, GERMANY, ASSIGNEES TO
FRIED. KRUPP AKTIENGESELLSCHAFT, OF ESSEN-ON-THE-RUHR, GERMANY.

SELF-DISCHARGING CAR.

Application filed March 28, 1921. Serial No. 456,371.

To all whom it may concern:

Be it known that we, WILHELM WINTER, residing at Essen, Germany, and GERHARD IMMAND, residing at Essen, Germany, both 5 citizens of the Republic of Germany, have invented a certain new and useful Improvement in Self-Discharging Cars, of which the following is a specification.

This invention relates to self-discharging 10 cars provided with a discharging flap which opens automatically under the action of the weight of the load and also under the action of its own weight. The object of the invention is to protect in a simple manner the 15 discharging flap, when in the closed position as well as in an open position, from any unintentional movement.

The invention will be described with reference to the accompanying drawing which 20 illustrates one embodiment of the subject matter of the invention and in which:—

Fig. 1 shows an end view of the self-discharging car in the closed position,

Fig. 2 is a similar view of the car with the 25 doors or flaps in the open position.

Figs. 3 to 5 show, in similar views, several details of the car in different positions and on a larger scale.

A denotes the saddle-shaped bottom rigidly connected to the underframe of the car, 30 A¹ are the end walls, likewise rigidly connected to the underframe, and B denotes the side walls which are swingingly suspended on the end walls A¹ and form each a dis- 35 charging flap.

On the middle portion of each end wall A¹ there is mounted a two-armed lever, one arm of which is denoted by C and the other by C¹. The arms C and C¹ are connected to 40 the side walls B by means of rods D. Each arm C¹ of the two arm levers C C¹ (the one of which covering the other in the drawing) forms together with a crank arm E mounted on the underframe, and with a coupling rod F connecting the crank arm E to the arm C¹. The coupling rod F has a slot into which engages the crank tap c² connecting the rod F with the crank arm C¹ so that the latter can turn through an angle corresponding to the 45 length of the slot independently of the crank arm E or of a mutual turning movement of the parts E and F.

When the side walls B, forming the dis- 50 charging flaps of the car, are in the closed position (see Fig. 1) the crank arm E, which

carries a weight e¹ disposed on one side thereof, assumes an angular position, in which it has passed beyond its dead position by a small angle in the direction opposite to the arrow x (see Fig. 3) and bears, by means 60 of a bolt e² mounted on one side thereof, against the coupling rod F in such a manner that it is prevented from further rotation in the direction opposite to the arrow x. The bolt e² is then held in locking relationship 65 with respect to the coupling rod F. At the same time the tap c² of the crank arm C¹ bears against the coupling rod F on the inner end of the slot.

In order to rotate the shaft on which the 70 crank arms E are mounted, a hand lever H (shown in Fig. 5) is provided which can freely rotate, in the well known manner, within convenient limits with respect to the crank shaft and which can couple itself 75 to the crank shaft in the desired direction when it assumes its end positions.

When the discharging flaps B assume the 80 closed position illustrated in Fig. 1, the load of the car exerts forces upon these flaps which forces are transferred, through the intermediary of the rods D, to each of the two-armed levers C C¹ in such a manner that the tap c² bears with pressure against the coupling rod F (see also Fig. 3). Consequently, the coupling rod F exerts a force, along its longitudinal direction, on the crank arm E which force tends to rotate this crank arm in a direction opposite to the arrow x. This rotation is, however, prevented by the 85 tap c² abutting on the coupling rod F; the flaps B, therefore, are secured in their closed position in a self-locking manner under the pressure of the load.

When the car is to be discharged, the crank 90 arms E are turned, by means of the above mentioned hand lever, in the direction of the arrow x. When this takes place the bolts e² are lifted from their respective coupling rods F and the two-armed levers C C¹ execute, after a very small clockwise movement, a rotation in the counter-clockwise direction. As soon as the crank arms E have passed 95 beyond their dead positions by a small amount, they continue to rotate in the direction of the arrow x, under the action of the forces produced by the load and independently of the hand lever. Then, the rods C C¹ continuing their rotation in the counter-clockwise direction, the crank arms E reach their 100 105 110

position of reverse (see Fig. 4) and change their direction of rotation. Finally, after having passed through their other dead position under the swing effect of the weights e^1 , 5 the crank arms E assume the angular position shown in Figs 2 and 5, where the bolts e^2 again bear against the coupling rods F and limit the rotation of the crank arms. After the crank arms E have reached this 10 other dead position, the flaps B swing still further by an amount corresponding to the length of the slots of the coupling rods F in the opening direction and then they return into the position shown in Fig 2 under 15 the action of their own weight, in which position the taps e^2 of the levers C C^1 (see particularly Fig. 5) rest again on the coupling rods F at the inner end of the slots. In this position the tap e^2 exerts, under the action 20 of the weight of the flaps B, a force upon the coupling rods F which coincides with the longitudinal direction of these rods and is transferred in the same direction as the crank E and tends to rotate the latter 25 further in the direction opposite to the arrow α into its other position of reverse. Since this further rotation of the crank E is prevented by the bolt e^2 resting on the coupling rod F, the flaps B are fixed, in an opening position 30 also, in a self-locking manner under the action of their own weight. As it results from the foregoing, owing to the presence of the slots within the coupling rods F, the positive connection between the levers C C^1 35 and the crank arms E is interrupted for a short time after these latter have attained their other dead position and, consequently, the crank arms E are able to pass with certainty automatically beyond their dead positions under the swing action of the weights e^1 . 40

In order to return the flaps B into the closed position the crank arms E are turned back, by means of the above mentioned hand lever, from the position shown in 45 Figs. 2 and 5 in the direction of the arrow α . When this takes place, the bolts e^2 are lifted from the coupling rods F and the levers C C^1 execute, after a very small rotation in the counter-clockwise direction, a 50 clockwise rotation. As soon as the crank arms E have passed beyond their dead position, by a small amount, they continue to rotate, under the action of the weight of the flaps B, in the direction of the arrow α 55 independently of the hand lever until they have reached again their position of reverse shown in Fig. 4. From this position the crank arms E move beyond their first dead position again into the original position 60 shown in Figs. 1 and 3, while the flaps B continue to approach to their closed position under the action of their own weight. In this case also the automatic passage beyond the dead position is secured by the 65 swing effect of the weights e^1 which main-

tain at the same time connection between the coupling rods F and the taps e^2 on the inner end of the slots of the coupling rods F during the backward rotation of the crank arms E.

70

We claim:

1. In combination with a car body having hinged flaps, a toggle joint means for controlling the simultaneous opening of said flaps, means to give to said first named 75 means a locked position past the dead center of said toggle, said toggle joint means comprising a lost motion connection for releasing the lock of said toggle without thereby giving the said flaps an oscillatory 80 movement.

2. In combination with a car body having hinged flaps, a toggle joint means for controlling the simultaneous opening of said flaps, means to give to said first named 85 means a locked position past the dead center of said toggle, said toggle joint means comprising a lost motion connection for releasing the lock of said toggle without thereby giving to said flaps an oscillatory 90 movement, and an energy storage means operated by said toggle joint means to aid in the unlocking movement of said connection.

3. In combination with means for opening and closing a flap or the like, a toggle joint, said opening means connected to one end of said toggle joint by virtue of a loose connection, said toggle having its members so arranged to permit of a movement past 100 the dead center line thereof, and further means to limit said movement past said dead center line.

4. In combination with means for opening and closing a flap or the like, a toggle 105 joint, said opening means connected to one end of said toggle joint by virtue of a loose connection, said toggle having its members so arranged as to permit of a movement past the dead center line thereof, 110 and further means to limit said movement past said dead center line, and still further means comprising an energy storing means for aiding said movement of the toggle past its dead center line position.

5. A saddle-bottomed dumping car having flap sides and comprising means for opening and closing a flap or the like, a toggle joint, said opening means connected to one end of said toggle joint by virtue of 115 a loose connection, said toggle having its members so arranged to permit of a movement past the dead center line thereof, and further means to limit said movement past said dead center line.

6. A saddle-bottomed dumping car having flap sides and comprising means for opening and closing a flap or the like, a toggle joint, said opening means connected to one end of said toggle joint by virtue of 120

125

130

a loose connection, said toggle having its members so arranged to permit of a movement past the dead center line thereof, and further means to limit said movement past 5 said dead center line, and still further means comprising an energy storing means for aiding said movement of the toggle past its dead center line position.

The foregoing specification, signed at Essen, Germany, this 17th day of February, 1921.

WILHELM WINTER.
GERH. IMMAND.
